UNITED STATES PATENT OFFICE

SAMUEL MILONE, OF CAMDEN, NEW JERSEY, ASSIGNOR, BY MESNE ASSIGNMENTS, TO
EARLE ANTI-FREEZE VALVE CORPORATION, OF CAMDEN, NEW JERSEY, A COR-
PORATION OF NEW JERSEY

ANTIFREEZE DEVICE FOR WATER SYSTEMS

Application filed March 13, 1930. Serial No. 425,559.

This invention relates to a device for preventing the freezing of water systems, particularly the cooling systems of automobiles, and comprises a thermostatically operated valve adapted to drain the system when the water therein reaches or closely approaches the freezing point.

Referring to the drawings:

Fig. 1 is a sectional elevation of the device forming the subject of my invention;

Fig. 2 is a sectional plan view taken on the line 2—2, Fig. 1; and

Fig. 3 is a sectional elevation taken on the line 3—3, Fig. 1.

The device comprises a casing 1 composed of a top cup-shaped section 2 and a bottom cup-shaped section 3, with a horizontal ring or plate 4 interposed between the two sections.

Each of the sections 2 and 3 is provided with a circular outwardly extending flange 5, through which and the said plate 4 rivets 6 extend, to secure the whole together as a unit and to prevent tampering with the operating elements, within the casing 1, after these elements have been properly adjusted to function when the proper draining temperature is reached.

The top section 2 has a boss 7 formed on its upper end which is tapped and threaded as at 8 to receive a nipple or other threaded element, by means of which the device is adapted to be operatively connected to the bottom of the radiator or other equally low point in the water system to be controlled.

The lower section 3 is provided with a depending boss 9 in which, and the lower part of the section 3, is located a body of metal 10 which may be formed by molding the body of metal directly in the lower section 3, or by previously forming the body of metal into the desired shape and thereafter inserting and suitably securing it in place within the section 3. Formed in the boss 9 and partly in the body of metal 10 is a drain port 11 which flares outwardly within the body of metal 10 as indicated at 11^a to form a seat 12 for a ball valve 13 which normally rests on said seat.

The plate or ring 4 is open at its center and

is provided with a pair of spaced lugs 14 and 15 which extend downwardly into the lower section 3 and therein support, in the present instance, a hexagonal bar 16, one end of which rests in a circular opening 17 formed in the lug 14 and the other end of which is threaded and passes through a threaded opening formed in a boss 18 on the lug 15.

Spirally wound around the bar 16 is a thermosensitive element 20 which comprises two strips of metal 21 and 22 having different coefficients of expansion. These two strips of metal are suitably secured together by sweating, soldering or other well known means, to form the thermosensitive unit 20.

The thermosensitive unit 20 has one end closely wound about and flattened against the flat sides of the hexagonal bar 16, as illustrated at 23, to secure this end of the said unit 20 rigidly to said bar. The cylindrical body portion of said unit 20 comprises a series of convolutions 24 of substantially equal diameters spaced longitudinally of the bar 16, terminating at the free end in an arm or lever 25, which rests on and extends laterally from the supporting bar 16.

The outer end of the arm 25 of the thermosensitive unit 20 projects through a slot 26 formed in the upper end of a tongue 27, the lower end of which is suitably secured to the ball valve 13.

Adjustment of the mechanism, so that the valve 13 will be unseated when a temperature closely approaching the freezing point is reached, is made by turning the bar 16 so that the arm 25 may be set at the proper angle relative to the bar 16 to co-operate with the tongue 27 of the valve 13.

After the mechanism has been properly adjusted the sides of the boss 18 are flattened around and against the flat sides of the bar 16 to permanently retain the adjustment.

The casing 1 is then assembled around the operating mechanism and the rivets 6 set to prevent tampering, as above noted.

The threads on the one end of the bar 16 co-operating with the threads formed in the boss 18 prevents longitudinal movement of the bar 16 and the flattening of the boss against the flat sides of the bar 16 prevents

turning thereof after adjustment has been made.

In operation the valve 13, resting on the seat 12, normally closes the drain port 11 and retains the water in the system. As the temperature of the water in the system approaches closely to the freezing point, that is, for example, within one-half of one degree above the freezing point, or $32\frac{1}{2}$ ° F. the thermo-sensitive element 20 will operate to turn the arm 25 thereof in a direction to raise the valve 13 from its seat 12, thereby permitting the water to be drained from the water system through the drain port 11.

Turning of the arm 25 is effected by the different expansion coefficient of the respective metallic strips 21 and 22 of which the thermosensitive element 20 is composed, contracting in different proportions, the outer strip 21 contracting more rapidly than the inner strip tending to unwind or straighten the element 20 and this action causing the arm 25 to fulcrum about the bar 16 and thereby unseat the valve 13. Obviously an increase in the temperature will tend to turn the arm 25 in the opposite direction and thereby press the valve 13 more tightly against the seat 12.

I claim:

1. In an anti-freeze device for water systems, the combination of a drain valve for connection in said system, and a thermostatic control for said valve, said thermostatic control comprising a supporting bar, a bimetallic strip formed into a substantially cylindrical form around said bar, one end of the strip being secured to the bar and the opposite end of the coiled strip terminating in an arm fulcrumed on said bar and operatively connected at its free end to said valve.

2. In an anti-freeze device for water systems, the combination of a drain valve for connection in said system, and a thermostatic control for said valve, said thermostatic control comprising a supporting bar, a bimetallic strip formed into a substantially cylindrical form consisting of a plurality of convolutions of substantially equal diameter coiled around said bar and spaced longitudinally thereof, one end of the strip being secured to the bar and the opposite end of the coiled strip terminating in an arm fulcrumed on said bar and operatively connected at its free end to said valve.

3. In an anti-freeze device for water systems, the combination of a casing having an inlet adapted to be connected to a water system and an outlet adapted to permit the draining of said system through said casing, a valve within the casing and normally closing said outlet, a bar supported within said casing, and a thermosensitive control element within the casing and operatively connected to said valve, said element comprising a bimetallic strip having one end secured to said

bar and the remainder of the strip formed into a cylindrical body composed of a plurality of convolutions of substantially equal diameters spaced longitudinally of said bar and surrounding said bar, said strip terminating in an arm extending laterally from and adapted to fulcrum about said bar, said arm being operatively connected to said valve.

4. In an anti-freeze device for water systems, the combination of a casing having an inlet adapted to be connected to a water system and an outlet adapted to permit the draining of said system through said casing, a valve within the casing and normally closing said outlet, a thermosensitive control element within the casing and operatively connected to said valve, means located entirely within the casing for adjusting the said thermosensitive control element, and means for permanently sealing the casing after the adjustment of said element has been made.

5. In an anti-freeze device for water systems, the combination of a casing having an inlet adapted to be connected to a water system and an outlet adapted to permit the draining of said system through said casing, a valve within the casing and normally closing said outlet, a bar supported within said casing, a thermosensitive control element within the casing and operatively connected to said valve, said element comprising a bimetallic strip having one end secured to said bar and the remainder of the strip formed into a cylindrical body composed of a plurality of convolutions of substantially equal diameters spaced longitudinally of said bar and surrounding said bar, said strip terminating in an arm extending laterally from and adapted to fulcrum about said bar, said arm being operatively connected to said valve, means located entirely within said casing for turning said bar to adjust said arm relative to said valve, and means for permanently sealing said casing after said adjustment has been made.

6. In an anti-freeze device for water systems, the combination of a casing having an inlet adapted to be connected to a water system and an outlet adapted to permit the draining of said system through said casing, a valve within the casing and normally closing said outlet, a bar supported within said casing, a thermosensitive control element within the casing and operatively connected to said valve, said element comprising a bimetallic strip having one end secured to said bar and the remainder of the strip formed into a cylindrical body composed of a plurality of convolutions of substantially equal diameters spaced longitudinally of said bar and surrounding said bar, said strip terminating in an arm extending laterally from and adapted to fulcrum about said bar, said

arm being operatively connected to said valve, means located entirely within said casing for turning said bar to adjust said arm relative to said valve, means for permanently securing said bar in its adjusted position, and means for permanently sealing said casing after said adjustment has been made.

7. In an anti-freeze device for water systems, the combination of a casing having an inlet adapted to be connected to a water system and an outlet adapted to permit the draining of said system through said casing, a valve within the casing and normally closing said outlet, a thermosensitive control element within the casing and operatively connected to said valve, means located entirely within the casing for adjusting the said thermosensitive control element, said casing comprising a pair of cup-shaped sections with their open sides adjacent each other, a plate interposed between the said sections of the casing and adapted to support the said operating elements of the device, and means for permanently securing the said sections of the casing together adapted to be applied after the said adjustment has been made.

8. In an anti-freeze device for water systems, the combination of a casing having an inlet adapted to be connected to a water system and an outlet adapted to permit the draining of said system through said casing, a valve within the casing and normally closing said outlet, a thermosensitive control element within the casing and operatively connected to said valve, means located entirely within the casing for adjusting the said thermosensitive control element, said casing comprising a pair of cup-shaped extensions with their open sides adjacent each other, an outwardly extending flange on and adjacent the open side of each section, a plate interposed between the flanges of said sections of the casing and adapted to support the said operating elements of the device, and rivets passing through said flanges and said plate, adapted to be set after the said adjustment has been made to permanently secure the elements of the casing together.

9. In an anti-freeze device for water systems, the combination of a casing comprising a pair of cup-shaped sections, a flange extending around each section adjacent the open side thereof, a plate interposed between said flanges, said sections and said plate having openings permitting the passage of water through the casing, a valve controlling the passage of said water through the opening in one of said sections, lugs on said plate, a bar supported by said lugs, a thermosensitive element comprising a bimetallic strip formed in a series of convolutions around and spaced longitudinally of said bar, one end of said strip being rigidly secured to said bar and the opposite end of said strip terminating in an arm extending laterally from said bar and op-

eratively connected to said valve, means for securing said bar against movement with respect to said plate, and rivets passing through said flanges and said plate to permanently secure the casing sections together.

10. In an anti-freeze device for water systems, the combination of a casing comprising a pair of cup-shaped sections, a flange extending around each section adjacent the open side thereof, a plate interposed between said flanges, said sections and said plate having openings permitting the passage of water through the casing, a valve controlling the passage of said water through the opening in one of said sections, lugs on said plate, a flatsided bar supported by said lugs and having threads formed on one end which cooperate with threads formed in one of the lugs, a thermosensitive element comprising a bimetallic strip formed in a series of convolutions around and spaced longitudinally of said bar, one end of said strip being rigidly secured to said bar and the opposite end of said strip terminating in an arm extending laterally from said bar and operatively connected to said valve, a boss formed on one of said lugs and having its wall depressed against a flat side of said bar for preventing rotation of said bar, and rivets passing through said flanges and said plate to permanently secure the casing sections together.
